UNITED STATES PATENT OFFICE.

MICHAEL J. DALY AND THOMAS S. LEAKE, OF CHICAGO, ILLINOIS.

WINDOW.

No. 862,451.

Specification of Letters Patent.

Patented Aug. 6, 1907.

Application filed September 10, 1906. Serial No. 333,881.

To all whom it may concern:

Be it known that we, MICHAEL J. DALY and THOMAS S. LEAKE, citizens of the United States, residing at Chicago, in the county of Cook and State of Illinois, 5 have invented new and useful Improvements in Windows, of which the following is a specification.

The invention relates to windows and particularly to that class of windows in which the sashes are arranged to swing inwardly as well as to slide up and down.

10 The invention has for its object to provide new and improved constructions and arrangements in the attachment and balancing of the sashes.

The invention also contemplates certain other new and improved constructions which will be made apparent by the following description:

The invention is illustrated in the accompanying drawings wherein

Figure 1 is an elevation of a window taken from the inside, parts of the frame being broken away; Fig. 2, a 20 sectional view on line 2—2 of Fig. 1; Fig. 3, a horizontal sectional view of the window and its casing, the sashes being shown in a different position from that of the previous figures; Fig. 4, a vertical sectional view on line 4—4 of Fig. 1; Fig. 5, a cross section on line 25 5—5 of Fig. 1; Fig. 6, a cross section on line 6—6 of Fig. 1; Fig. 7, a cross section on line 7—7 of Fig. 1; Fig. 8, a detail of the hinged guide with its fastener; Fig. 9, an elevation of one of the sliding tongues to which the window sashes are attached; Fig. 10, a cross section on 30 line 10—10 of Fig. 9; Fig. 11, a longitudinal section through one of the sash balance pulleys, and Fig. 12, a section on line 12—12 of Fig. 11.

Like letters of reference indicate like parts in all the drawings.

35 The various parts of the window frame, which is of ordinary construction, are indicated by the letters A, A.

B represents the jamb on one side of the window and B¹ the jamb on the other. The window frame is preferably constructed so that a recess B² is formed back of 40 the jamb B. There may also be a recess B³ back of the jamb B¹. The window is shown as having two sashes, an upper sash C, and a lower sash C¹. These sashes are constructed and attached to the frame of the window so as to slide up and down in the customary way and 45 also to be capable of being swung inward into the room. The arrangement is the same with respect to each of the sashes so we shall confine the description to one sash.

On the jamb B are strips D, D, one for the upper and one for the lower sash. These strips are formed with 50 longitudinal slots D¹ having inner enlargements D². The strips may be made of metal or they may be made of wood, in which case they can be formed in two parts as shown. If of wood they will preferably be thoroughly soaked in oil. The slot D¹ with its enlargement D² is designed for a sliding tongue piece E, shown 55 in detail in Figs. 9 and 10, and which consists of a shank

E¹, a cross piece E², and a cylindrical extension E³ which will preferably be formed by turning the shank over upon itself, as is shown in the cross section of Fig. 10. The sash C is hinged to this sliding tongue E. 60 We have shown two hinges for each sash, one of which is illustrated in detail in Fig. 6. It consists of a sheet of metal F having a cylindrical bend F¹ to extend around the part E³. The plate F is secured to the front of the side rails C² of the sash by means of grooves F² F², 65 and has a right angle extension F³ beyond the curved part F¹ which passes through a slot E⁴ in the shank E¹ of the tongue piece and is fastened by means of a screw F⁴ to the side rail C². Any desired form of hinge might be adopted but the above we have found to give very secure attachment. It will be understood that all of the 70 hinges may be constructed in the same manner.

The sashes are designed, either to slide up and down or to be swung inwardly on their respective tongue pieces E, E as pivots. It is, therefore, necessary to 75 provide on the other side of the window a connection between the sash and frame which will permit the sliding of the sashes upon the frame and also their disengagement from the window frame when they are to be swung inwardly. It is important that this connection 80 be a snug one so as to keep out wind and cold and prevent rattling. To this end we provide each of the sashes with a removable guide piece adapted to slide in the window frame but capable of being retracted in case the sash is to be opened inwardly. This guide 85 and its attachments are illustrated particularly in Figs. 1, 3, 7 and 8. It consists of a strip or plate G hinged at G¹ to the right hand side rail C² of the sash and bent around at G² so as to conform to a groove B⁴ in the jamb B¹. There will, of course, be two of these 90 grooves, one for each of the sashes. The part G² of the guide is preferably formed with a rib G³ and is slotted at G⁴ to receive the loop G⁵ of a clip G⁶ to which is pivoted at G⁷ a latch G⁸ having slots G⁹ G⁹. The latch 95 extends through a slot G¹⁰ in the flange G¹¹ of a plate G¹² which is secured by screws G¹³ G¹³ on the front of the side rail C². In Fig. 8 the guide is shown as locked in the position it takes when in engagement with the jamb of the window. When the sash is to be swung inwardly the latch G⁸ is lifted, drawn inward toward 100 the window pane until the other of the slots G⁹ is engaged by the flange G¹¹. The guide will then be free of the jamb so that the window may be swung on the part E³ as a pivot as shown in Fig. 3. It will be seen that the connection between the sash and the jamb is 105 a very close one, but one, however, which permits perfect freedom in moving the sashes up and down.

The sashes may be balanced in any desired manner. We have shown, however, a preferred method of sash balance construction involving several innovations 110 and which is suitable perhaps to other forms of window than the one we are describing in this specification,

- but which is particularly adapted to the construction herein shown. This construction of sash balance contemplates balancing the sashes, one against the other, on a single cord and by the use of a single weight.
- 5 While this arrangement is not in itself new, the construction here shown involves certain improved devices and arrangements obviating defects incident to this method of balancing the sashes of a window.

The cord H, attached at one end by means of a split 10 ring H¹ to the lower sash C, passes from a small deflecting wheel J around a pulley K, then down around a pulley L in a block L¹ to which is attached the weight M, up over a second deflecting wheel J¹, around a pulley K¹, and then to the upper sash C to which it is attached 15 by a split ring H².

The attachment to the sashes may be made in any desired manner. We have shown in the drawings a clip N bent at N¹ to embrace the part E³ of the sliding tongue E, and pinned thereto by the pin N². This 20 clip has the extension N³ with the perforation N⁴ to receive the split ring on the cord H. It will be understood that we use the word "cord" in general to indicate any rope, chain, or other means for supporting the sashes.

25 Where the two sashes of the window are balanced by a single weight it has been found that a quick movement of one of the sashes may disturb the position of the other. To lessen this effect we prefer to construct and arrange our pulleys in a peculiar manner. One 30 or more of the pulleys are preferably constructed so that there will be a considerable friction between the rotating part of the pulley and its axis or core. The pulley will, therefore, be somewhat sluggish, tending to brake the action of the movement of the sashes one 35 upon the other. This effect is increased by the use of deflecting wheels or pulleys which, moreover, give a compact construction. We have shown, in Figs. 11 and 12, a preferred construction of pulley and deflecting wheel, these drawings showing the construction, 40 for example, of the pulley K and deflecting pulley J. These pulleys are mounted in a block which is set into a slot in the jamb B. The block is preferably made in two halves, the line of jointure being indicated at X, X. The block, when the halves are assembled consists 45 of a front plate K² which has a perforation K³ for the screw K⁴ by means of which it is secured to the jamb B. Integral with the two halves of the plate K² are backwardly extending plates K⁵ which have the circular flanges K⁶ K⁷ forming a core or axle for the 50 pulley wheel K⁷ which extends through a slot in the plate K². The plates K⁵ have the integral extensions K⁸ below the core flanges K⁶ K⁷ and between the plates at this point is the axle J² of the deflecting pulley J. The two halves forming the block of the pulley carry 55 lugs K⁹ K¹⁰ perforated to receive the rivet K¹⁰ by means of which the assembled parts are held together.

I wish it to be understood that I do not desire to be limited to the exact details of construction shown and described for obvious modifications will occur to any 60 person skilled in the art.

The use and operation of our window will perhaps have been made sufficiently clear by the foregoing. To recapitulate, it will be seen that the sashes are

hinged to sliding members which preferably have a long bearing in the window frame. The sashes, together with these sliding members may, therefore, be pushed up and down in the ordinary way so as to open or close the window at top or bottom. When it is desired to swing the sashes inward, for example, for the purpose of cleaning the window, the guide pieces G 65 may be retracted and locked in the position shown at the right hand side of Fig. 3. The sashes can then be swung inward with perfect freedom. This construction, it will be seen, is very simple and economical. The sashes are at the same time tight enough to keep 70 out the weather and yet may be freely moved. The sashes, it will be seen, are balanced one against the other by a single cord and through the instrumentality of a weight which may be very much less, perhaps less than half the weight of the two sashes. By the use of 75 80 the pulleys of our construction arranged as above described, this novel method of balancing the sashes is perfectly practical.

I claim:

1. In a window, the combination of a window frame 85 having a slot in one side thereof, a window sash, a tongue piece slidably mounted in the slot, a cylindrical bearing part on the tongue piece, said tongue piece being slotted adjacent thereto, and an angle plate extending through the slot in the tongue piece and secured to the sash, and 90 having a curved part surrounding the cylindrical bearing part of the tongue piece and forming a hinge for the sash.

2. In a window, the combination of a window frame having a slot in one side thereof, a window sash, a tongue piece slidably mounted in the slot, a cylindrical bearing 95 part on the tongue piece, said tongue piece being slotted adjacent thereto, an angle plate extending through the slot in the tongue piece and secured to the sash, and having a curved part surrounding the cylindrical bearing part of the tongue piece and forming a hinge for the sash, and 100 a clip for the sash cord extending through the slot in the tongue piece and pinned to the cylindrical part.

3. In a window, the combination of a window frame with a sash, means for connecting the sash at one side of the window frame by sliding and hinged connections, the 105 frame on the other side being slotted, a retractable member hinged to the edge of the sash and normally extending into the slot in the window frame so as to slide therein, and means for withdrawing the same from the slot.

4. In a window, the combination of a window frame, 110 with a sash, means for connecting the sash at one side of the window frame by sliding and hinged connections, the frame on the other side being slotted with a slot triangular in cross section, a retractable member consisting of two strips set at an angle to each other, one of them overlapping the sash, and means for drawing the retractable member inward against the sash so as to free the same from the slot in the frame and permit the sash to be 115 swung.

5. In a window, the combination of a window frame, 120 with a sash, means for connecting the sash at one side of the window frame by sliding and hinged connections, the frame on the other side being slotted with a slot triangular in cross section, a retractable member consisting of two strips set at an angle to each other, one of them overlapping the sash, a latch hinged to the retractable member and a latch plate on the sash having a flange with 125 an opening through which the latch extends.
